UNITED STATES PATENT OFFICE.

HAMILTON CLAYTON BOGGS, OF DECATUR, ALABAMA.

INNER TUBE FOR PNEUMATIC TIRES.

1,227,108.

Specification of Letters Patent. Patented May 22, 1917.

Application filed July 3, 1916. Serial No. 107,423.

To all whom it may concern:

Be it known that I, HAMILTON CLAYTON BOGGS, a citizen of the United States, residing at Decatur, in the county of Morgan and State of Alabama, have invented certain new and useful Improvements in Inner Tubes for Pneumatic Tires; and I do hereby declare the following to be a full, clear, and exact description of the invention, such as will enable others skilled in the art to which it appertains to make and use the same.

My present invention relates to that general class of pneumatic tires known as "self-healing" tires, and to that particular type of said class in which a comparatively thick inner tube composed mainly of elastic rubber is used, and in which the material of the inner tube is held under compression instead of under tension when the said inner tube is mounted in the shoe or casing and inflated.

My present invention is intended more especially to provide certain improvements over the construction shown in my Patent No. 1,182,871, granted May 9, 1916, and entitled "Improvements in inflatable tires."

In the structure shown in that patent, when a perforation of any appreciable size is made in the shoe, the soft rubber of the inner tube will be forced by the pressure of the air within the same to project into the crack or opening and such projecting portion will be pinched off, the result being that in a short time a perforation will be made in the inner tube itself, and the same will become deflated.

According to my present invention, I provide a reinforce consisting of canvas embedded in the rubber of the inner tube, preferably near the exterior. This canvas may consist of a single layer or plurality of layers, and may be continued entirely around the inner tube, or so placed as to protect the portion only thereof that is liable to be forced up into the cracks or perforations in the shoe.

According to my invention, I provide an inner tube, which, when deflated, has walls of sufficient thickness to assume a yielding but relatively fixed cross section, that will

enable the tube to be inserted in or removed from the shoe without any danger of creasing or pinching, and yet, when the pneumatic pressure is applied, the tube will adapt itself to the inner contour of the shoe, compressing the rubber in the tube, and bearing firmly against the inner walls of the shoe. The thickness and body of the material in the tube will also tend to stiffen the casing, preventing the latter from folding or bending at sharp angles when in service. But when the inner tube becomes deflated from any cause, as from a leaky valve or the like, will fold upon itself in such a way as to interpose an elastic rubber cushion between the tread portion of the shoe and the rim of the wheel, thereby in a large measure preventing the cutting by the rim of either the shoe or the tube.

The exterior of the tube is initially made of somewhat greater circumference in cross section than the interior of the casing, so that when assembled the shoe will compress the rubber in the tube.

My invention will be understood by reference to the accompanying drawings, in which, Figure 1 shows a cross section through the shoe and the inner tube, the inner tube being deflated, but no external pressure being applied to the shoe.

Fig. 2 shows a similar section to Fig. 1, except that the inner tube has been inflated.

Fig. 3 shows the inner tube in the deflated condition, and pressure applied to the tread of the shoe, and illustrates the efficiency of the device against the cutting of the shoe by the rim; and

Fig. 4 shows a modification in which there are a plurality of plies of canvas throughout the major portion of the inner tube, and a single ply in that portion thereof next to the rim of the wheel.

A represents the shoe of the tire, which may be constructed in any usual or convenient way. In the various drawings, I have shown a tire of the clincher type, mounted in a well-known form of clincher rim C.

The inner tube B is made of molded rubber, preferably thicker in the portion b, adapted to engage in the tread of the shoe,

and thinner in the portion b' , adapted to project into those portions of the shoe which are protected against puncture by the rim C.

Embedded in this inner tube, preferably near its outer surface, I provide one or more strips of canvas D, which may extend entirely around the inner tube or may terminate at the points marked d , in Figs. 1 and 2, beyond which points, the inner tube and shoe are protected against puncture by the rim.

In Figs. 1 and 2, I have shown a single strip of canvas embedded in the outer portion of the inner tube, while in Fig. 4, I have shown double strips of canvas D, extending throughout those portions of the inner tube, that are most liable to be punctured, and terminating at the points d' from which points a single strip of canvas d^2 is carried around that portion of the tube next to the rim.

When deflated and in the normal position, the inner tube is constructed in a substantially heart-shaped cross section, shown in Fig. 1, in which the tip of the heart which projects in toward the rim is flattened somewhat as at 1, and bears against the rim, and the tapered sides 2 and 3 engage corresponding portions of the shoe or casing. The sides of the inner tube are provided with annular grooves 4 and 5, and the periphery of the inner tube is provided with an annular groove 6, between which grooves 4 and 6 and 5 and 6, there are U-shaped loops having bearing surfaces which engage the interior of the shoe at equi-distant spaces from the center of the tread of the shoe.

Thus, we have three annular depressions in the outer walls of the inner tube, which leave spaces lenticular in cross section between the outer walls of the tube and the inner walls of the shoe. When the inner tube is inflated its thick walls are forced outward under pressure into these lenticular spaces until they fit snugly against the inner walls of the shoe, the result being that the whole inner layers of the inner tube are placed under a state of compression, and if the inner tube is punctured as by a nail or the like, the wound is automatically closed by the compression of the rubber.

The canvas near the outer walls of the inner tube will give sufficient stiffness to the rubber to prevent it being forced into any puncture in the shoe, and thus the life of the inner tube is greatly prolonged, and there is little danger of deflation of the said tube except from leaky valves or other abnormal conditions.

By having the canvas reinforce near the outer wall of the inner tube, an armor therefor is provided without materially impairing the compression feature of the thick wall of the tube, while the thin layer of

rubber exterior to the canvas will prevent excessive rubbing of the canvas on the inner wall of the shoe.

Since the most of the perforations are likely to occur at or near the tread of the shoe, I preferably thicken these portions of the inner tube as at b and thereby give a better self-healing effect to the inner layers of compressed rubber at that point.

When from a leaky valve or any other reason, the inner tube does become deflated, the lower portion of the tire, or that portion pressing on the ground, will assume the position shown in Fig. 3, in which the thick walls of the inner tube are folded upon themselves, as shown and forming a resilient cushion, thus in a large measure protecting both the shoe and the inner tube from being cut or materially injured by the rim. When the tire is in this collapsed condition, the layer or layers of canvas being located near the exterior of the inner tube will serve to protect the inner rubber portions of the inner tube from rupture or abrasion.

While I have shown the tire as applied to a clincher rim, and shoe, it will be obviously applicable to any other well-known form of rim and shoe.

Having thus described my invention, what I claim and desire to secure by Letters Patent of the United States, is:

1. In a tire, the combination with a rim and a shoe connected thereto, of a continuous annular inner tube mounted in said shoe, said tube being made of soft rubber with comparatively thick walls, and reinforced with one or more layers of canvas embedded therein, near the exterior thereof, said tube being substantially heart-shaped in cross section when deflated, and the walls of said tube being of greater thickness at the outer periphery than at the inner periphery, said tube being provided with annular grooves in its sides and outer periphery, forming with the shoe when the tube is deflated, annular spaces, lenticular in cross section, whereby when the tube is inflated the walls of the tube are forced outward compressing the inner layers of rubber thereof, and filling up said lenticular spaces, and whereby, when the tire is collapsed, a yielding cushion is provided between the tread of the tire and the rim, substantially as described.

2. In a pneumatic tire, the combination with a casing of an inner tube therefor composed of a thick annular shell of soft rubber, made thicker on its outer than on its inner periphery and molded to a set form with one or more layers of canvas inserted in the body and near the outer periphery thereof, said tube being provided with a wide depression in the outer periphery thereof,

and with oppositely disposed similar depressions in the sides thereof, said depressions being separated by uninterrupted curved annular outwardly-projecting looped portions, adapted to engage and to have rolling contact with the interior of said casing, when deflated, the whole inner tube being adapted, when inflated, to form a contin-

uous, thick, elastic lining, held under compression by, and with its tread and side portions fitting snugly throughout against, the inner walls of said casing, substantially as described.

In testimony whereof, I affix my signature.

HAMILTON CLAYTON BOGGS.
